DES. 2442

Assignor to:

Edward C. Sampson of New York City

Letters Patent No. 8442, Dated Sept. 25, 1866.

Design for a Floor Oil Cloth Pattern.

The Schedule referred to in these Letters Patent and making a part of the same.

to all whom it may concern:

I, Charles J. Meyer of the Town of Bergen, County of Hudson and State of New Jersey, have invented or produced a new original and ornamental design for Floor Oil Cloth, Carpet and other fabrics, and do hereby declare that the accompanying drawing marked and designated as being the S. fully represents said design and is sufficient without further aid to enable any person skilled in the art to which it appertains to repeat it for practical use.

The colors and the arrangement of them, may in the use of the design be varied to suit the taste or fancy of the user, or manufacturer of articles ornamental by said design. This design may be of any size or colors in kind or number, or in any contrast or blending of colors of light and shades.

I claim as new and desire to secure by Letters Patent of the United States, the Design for Floor Cloths, Carpets &c, as shown and described.
